UNITED STATES PATENT OFFICE.

CHARLES N. CHADWICK, OF BROOKLYN, NEW YORK.

CORSET.

SPECIFICATION forming part of Letters Patent No. 274,272, dated March 20, 1883.

Application filed December 7, 1882. (Model.)

To all whom it may concern:

Be it known that I, CHARLES N. CHADWICK, of Brooklyn, in the county of Kings and State of New York, have invented a new Improvement 5 in Corsets; and I do hereby declare the following, when taken in connection with accompanying drawings and the letters of reference marked thereon, to be a full, clear, and exact description of the same, and which said drawings constitute part of this specification, and represent, in—

Figure 1, a side view; Fig. 2, a transverse section through the strip 1; Fig. 3, the hip-section; Fig. 4, the front, with the overlying 15 flaps for the stays.

This invention relates to an improvement in corsets, with special reference to the hip-section, and such as are provided with a certain amount of elasticity in that section.

20 In order that a corset may fit a person with ease and yield to the movements of the body, elastic devices have been introduced at different points, top and bottom. In some cases this has been done by cutting out a portion of 25 the corset and extending elastic strips across the opening. In other cases elastic gores have been introduced; but generally with such elastic devices a difficulty has been experienced in the liability of the corset to curl or wrinkle. 30 Again, in the use of this class of corsets, in which an opening has been left in the corset, the opposite edges connected by elastic strips, a serious objection arises, from the fact that the garment and flesh of the wearer protrude 35 through the opening and interfere materially with the comfort of the wearer, as well as the shape of the person desired to be given by the corset.

The object of my invention is to overcome 40 these difficulties; and it consists in a corset constructed with a vertical opening or openings from the bottom upward, and from the top downward, either or both, toward the waist-line, one portion constructed with an extension to pass inside the other, leaving the two parts free to play the one upon the other, and the edge of the outer or overlapping part provided with a stay hinged to the body of the corset near the waist-line, its free end connected 45 to the underlying part at a point distant from the flaps *a b*, and so as to draw the outer part

over the under part, yet permit the free play of the parts.

In illustrating my invention I show it as applied to the hip-section. A represents the 55 rear portion, and B the front portion; C, the hip-section, which connects the front and rear, and extends from under the arm down over the hip. At the rear edge of the front section, B, I form a flap, *a*, at the bottom, and *b* at the 60 top, extending backward onto the hip-section. They may be cut as a part of the front section, or made separate and attached to the rear edge of the front section. They extend to near the waist-line, and at their waist end are left free 65 from the section, to which they are attached or made a part of by a slit, *d*. (See Fig. 4.) The flaps *a b* are each formed with a pocket to receive the stay.

The hip-section C is cut at the central portion to meet the front portion, as from *e* to *f*, and is stitched to the central part of the rear edge of the front section, B, but left free above and below, and above and below the points where attachment is made the section has extensions D E, (see Fig. 3,) which underlie the flaps *a b* when the parts are stitched together. The flaps *a b* are pivoted to the body of the corset, as at *h*, at the apex of the slit, near the waist-line, so as to leave the flaps *a b*, with the 80 stays in their pockets, free to turn upon that pivoted point, either to the front or rear. The free ends of the flaps *a b* are connected by an elastic strip, *l*, outside of and to a point on the hip-section at or near its opposite edge, which 85 completes the corset. The hinged or pivoted flaps or pockets inclosing stays overlap the adjacent part of the corset, so that as it is expanded by the shape of the wearer or movements of her body no opening is produced in 90 the corset. It fits as closely as if the corset were without slit or opening. The flaps inclosing stays, being hinged to the body of the corset, readily turn forward or backward without the usual bending, as where the stay extends from top to bottom they must bend transversely as the shape of the body varies.

While I prefer to make the opening at the top and bottom of the corset, it may be only at the top, or only at the bottom.

The underlying extensions D E may be provided with stays, in the usual manner of stay-

ing corsets, and generally should be stayed, as they will keep their place better than without stays.

5 While I prefer to make the openings at the front edge, they may be made at the rear. In that case the hinged stays will be placed at the rear, the elastic strips *l* extending forward, and the underlying extensions would be backward instead of forward, it only being essential to the invention that the outer or overlying edge shall be provided with the hinged stay, and that the underlying part shall have an extension over which the stay will play backward and forward, and the free end of the hinged stay connected by an elastic strip to an opposite point on the section.

This illustration, as applied to the hip-section, will be sufficient to enable those skilled in the art to apply the same to other parts in 20 the corset where elasticity is desirable.

I claim—

1. A corset constructed with vertical slits

extending to near the waist-line, one edge provided with a pocket inclosing a stay hinged to the body of the corset at the apex of the slit, 25 an extension from the opposite edge beneath, and so as to underlie the stay-pocket, and over which the hinged stay-pocket will freely move, and an elastic connection from the free end onto the part having the underlying extension, substantially as described.

2. A corset constructed with vertical slits extending to near the waist-line, one edge provided with a pocket inclosing a stay, an extension from the opposite edge, beneath and 30 so as to underlie said pocket, and over which the pocket will freely move, and an elastic connection from the free end onto the part having the underlying extension, substantially as described.

CHARLES N. CHADWICK.
